UNITED STATES PATENT OFFICE

2,191,699

ROCK DRILL

Henry M. Stephens, Montgomery, W. Va.

Application January 16, 1939, Serial No. 251,172

1 Claim. (Cl. 255—64)

This invention pertains to earth boring devices and more particularly to an improved drill or bit for use with concussion or impact type boring or drilling hammers more commonly referred to as 5 pneumatic hammers.

Viewed from another aspect, it is an object of the invention to provide a rock drill of increased efficiency with a removable or replaceable bit piece having cutting teeth arranged in a particular manner so that certain of the teeth will act as pilots while other teeth act as reamers as well as cutters.

Another object is the provision of a drill bit of the class described and particularly suited for use with pneumatic hammers, the bit being provided with air passages for directing air from the hammer into the work head of the bit for the purpose of driving finer particles away from the bit in its breaking or boring operation.

Another and more particular object is the provision of a rock drill or analogous device in the form of a shank member adapted to fit into a pneumatic hammer and having a bit piece removably secured to an end thereof, there being an air passage through the shank member and the bit piece for directing exhaust air into the drilled hole to remove finer particulate matter, and the bit piece having a plurality of angularly arranged teeth, at least one of which is disposed in advance 30 of the others as a pilot.

Another object is the provision of a rock drill of the class described particularly suited for use in drilling machines capable of imparting both impact and rotative movement to the bit, the 35 drill bit being provided with a plurality of angularly disposed teeth arranged for both reaming and cutting action.

Other objects and advantages of the invention reside in certain details of construction as well 40 as the mode of operation of the illustrative embodiment described hereinafter in view of the annexed drawing, in which:

Fig. 1 is a perspective view of the pneumatic hammer employing the new bit or drill;

Fig. 2 is an enlarged elevational view of the bit;

Fig. 3 is a fragmentary section through the bit head as seen in the direction of line 3—3 of Fig. 2; while

Fig. 4 is an end view of the bit head looking in 50 the direction of line 4—4 of Fig. 3.

In the preferred form of the device shown in Fig. 2, there is provided an elongated shank member 10 of suitably hardened steel and preferably hexagonal in surface contour for greater strength, 55 there being a shoulder 11 provided near the upper

end, and the portion of the bit between the shoulder and the upper end constituting a seating portion 12 which is receivable in the chuck of the hammer.

At its lower end, the shank is slightly reduced and provided with a reverse threading 13 which runs in opposition to the normal direction of rotation of the drill in operation. The work-engaging portion of the bit is in the form of a nipple 14 which threads onto the threading 13 and 10 which is provided with a plurality of cutting teeth at its free outer end.

The arrangement of the cutting teeth is one of the important features of the invention, there being a central or pilot tooth 16, the point of which 15 lies on the center line through the drill and which extends appreciably in advance of the points of the remaining teeth. The central or pilot tooth is flanked by reaming teeth 17, the points of which terminate at the outer marginal extremities of the nipple and lie behind the point of the pilot tooth. The pitch of the reaming teeth relative to that of the pilot tooth is so designed that their inner sides form obtuse angles with the sides of the pilot tooth and hence the maximum 25 space will be left between the several teeth as the same are driven into the rock or other matter, so that broken particles may escape more rapidly whether the drill is being employed only in reciprocatory or straight concussion movement, or in 30 a combination concussion and turning movement.

In other terms, the flanking teeth have their inner sides sloped as much as possible away from the central tooth to minimize the trapping of particles between the teeth, while at the same 35 time providing an adequate cutting edge at the apex of each flanking tooth. In this sense, the outer teeth are sloped a maximum away from the central tooth to provide an optimum cutting efficiency with minimized particle trapping spaces 40 between the teeth.

Another novel feature is the provision of pneumatic means for assisting in driving away broken particles from the head of the bit, this means including a concentric passage 20 leading from an 45 entrance opening 20a at the upper end of the shank to an exit 20b (Fig. 3) at the lower threaded end thereof, the nipple 14 being provided with a chambered portion 21 registering with the exit 20b and communicating with a plurality of angularly directed exhaust passages 22 leading from the region just above the central tooth on opposite sides of the latter.

In operation the drill 10 has its upper portion 12 fitted into the chuck 30 of a hammer or driv- 55

ing member such as the pneumatic hammer 31, the shoulder 11 limiting movement of the portion 12 into the chuck, and the hammer being of a type adapted to direct exhaust air into the entrance 20a of the air duct in the drill. The hammer is manipulated in the usual manner with the drill held in a substantially vertical position so that the pilot tooth 16 will properly drive in advance of the companion teeth, as illustrated 10 by the dotted line representation in Fig. 2. The cutting speed of this drill is greatly increased due to the action of the pilot tooth and also due to the action of the air blast in removing particles rapidly from beneath the drill head. Moreover, 15 where the hammer or other drilling tool is of a type adapted to rotate the drill bit as well as drive the same, the teeth 17 also act as reamers, thus further increasing the effectiveness of the drill and providing a substantially clean-cut hole.

20 The trident arrangement of the cutting formations particularly described herein has been found to be most satisfactory, but it will be appreciated that additional teeth may be arranged with respect to the pilot tooth to the same advantage.

25 It will be apparent that the invention provides a more effective drill suited for either simple impact or compound impact and rotative motion and one in which the arrangement of teeth provides for greater cutting efficiency in both simple and compound motions, the pilot tooth effecting a 30 lead break which is immediately taken advantage of by the following flanking teeth. Where the motion is compound, rotation of the flanking teeth imparts a reaming action which further 35 reduces the resistance to the drill. The angular relationship of the several teeth permits a quicker expulsion of the particles and pulverulent matter, which is further and quickly expelled through

the action of the air blast. This air blast it may be pointed out also assists in keeping the drill head cool.

The several objects and advantages of the invention may be realized in variant forms of the 5 particular embodiment described for purposes of illustration, and the appended claims are therefore intended to include all modifications and equivalent arrangements.

Having thus described my invention, what I 10 claim as new and desire to protect by Letters Patent is:

A rock drill bit consisting of a body member of substantially cylindrical shape and provided with means at one axial end thereof adapted for 15 attachment to a shank member, the opposite axial end of the body member being provided with teeth lying along a line extending diametrically across said end, said other end of the body member having portions flanking said teeth and sloping 20 outwardly away therefrom, means providing egress for scavenging air in the region of the juncture of said teeth with said outwardly sloping portion of the body member, and the latter being further provided with means for conducting 25 air from said shank member through said air passage means for the scavenging air, said other and outwardly sloping end portions of the body member being notched at their juncture with the cylindrical side wall portions of said member to 30 provide escape for scavenging air cooperably with the outwardly sloping portions of said other axial end to provide for escape of scavenging air when said teeth are substantially imbedded to the depth of their juncture with said other axial end of 35 the body member.

HENRY M. STEPHENS.
